OIL WELL PUMPING APPARATUS

Marshall C. Turner, Bartlesville, Okla., assignor to Phillips Petroleum Company, a corporation of Delaware

Application October 25, 1954, Serial No. 464,495

7 Claims. (Cl. 103—179)

This invention relates to improvements in oil well production apparatus. A specific aspect of the invention pertains to apparatus for separately producing oil and gas from the lower producing zone in a dual-zone well.

In dual-zone wells wherein oil and gas are produced from each of two separate zones without comingling the production from said zones, existing pack-off equipment necessary for fluid segregation prevents gas-oil separation when a displacement pump is used. Of course gas-oil separation is desirable and advantageous.

An object of the invention is to provide novel apparatus for separately flowing gas and oil from the lower producing zone of a dual-zone well. Another object is to provide improved apparatus for simultaneously producing both zones of a dual-zone well with separation of gas and oil from the lower producing zone. It is also an object of the invention to provide an oil well pumping installation which pumps from below a packer and effects bottom hole separation of oil and gas. Other objects of the invention will become apparent from a consideration of the accompanying disclosure.

The invention utilizes one tubing string extending to the lower producing zone for gas flow and a reciprocating macaroni tubing string for oil flow to an intermediate point in the well from which point to the ground surface a solid sucker rod is utilized to operate the reciprocating tubing section. At the point of juncture of the reciprocating macaroni tubing section or hollow sucker rod with the solid sucker rod, a cage or spider or similar device is utilized in the connection between the solid sucker rod and the hollow sucker rod so as to permit flow of oil from the hollow sucker rod through the cage into the tubing-sucker rod annulus from which it flows to the take-off from the well head. A plunger-seal at the upper end of the hollow sucker rod shuts off the flow of gas to the tubing above the plunger-seal and perforations in the tubing in this area permit the gas to flow outwardly into either a concentric tubing extending to the well head or through a small parallel tubing string serving the same purpose. This auxiliary tubing for gas flow is packed off at the lower end to seal the tubing from the annulus between the casing and the tubing and thereby maintain separation of fluids flowing from the upper and lower producing zones.

The equipment with which the invention is concerned provides a bottom hole pump in the liquid from the lower producing zone, or in proximity thereto, connected with a macaroni tubing string or hollow sucker rod. The tubing in the area in which the pump is located is perforated and the casing-tubing annulus is blocked off, thereby allowing entry of oil and gas into the annulus between the macaroni tubing and the main tubing. The top of the pump plunger is equipped with a blind cage which is coupled to the hollow sucker rod or tubing. Gas separates from the oil in the tubing-sucker rod annulus and flows to the surface via this annulus; the aforesaid perforations in the tubing, and the auxiliary tubing

extending to the well head. The location of the plunger-seal is dependent upon the tensile strength of the small tubing or hollow sucker rod. In deep wells hollow sucker rod is of insufficient strength to permit extension from the bottom hole pump to the well head and it is therefore essential to restrict the length of the hollow sucker rod section or string to that which will not exceed the tensile strength of the sucker rod, and then complete the string to the well head with solid sucker rod of sufficient strength to support the string. The plunger-seal may comprise a section of the upper end of the hollow sucker rod or an expanded section thereof and a seal between the same and the surrounding tubing which permits movement of the plunger without allowing gas to continue up the tubing around the plunger.

More complete understanding of the invention may be had from a consideration of the drawing of which Figures 1 and 1-A are an elevation, partly in section, of one embodiment of the apparatus of the invention broken at line a—a; Figures 2 and 2-A are an elevation, partly in section, of another embodiment of the invention broken at line b—b; and Figure 3 is a sectional elevation of a section of the apparatus in the area of the plunger-seal showing another embodiment of the plunger-seal arrangement. All of the views are schematic.

Referring to Figures 1 and 1-A, a well bore having a casing string 11 communicates with an upper producing zone through perforations 12 and with a lower producing zone through perforations 13. A tubing string 14 extends from the well head 16 to the area of the lower producing zone. Within tubing 14, extending down from the well head, is solid sucker rod 17 which connects with a hollow sucker rod 18 extending to the liquid in the lower producing zone. Solid sucker rod 17 is connected by cage 19 and plunger 21 to hollow sucker rod 18. A sealing means 25 is positioned in the annulus immediately surrounding the plunger so as to form a seal with tubing 14. An auxiliary conduit 23 extends from the well head to a position below sealing means 25 and is packed off by means of packer 24. Perforations 26 in tubing 14 intermediate packer 24 and sealing means 25 provide for flow of gas from tubing 14 into auxiliary tubing 23 and thence to the surface.

45 A packer 27 is positioned at a level intermediate the lower production zone and the upper production zone to separate the fluid from the two zones and provide an enclosed annulus between the casing and the tubing for flowing the oil and gas from the upper producing zone to the surface. Perforations 28 in tubing 14 below packer 27 provide a path for flow of oil and gas into the tubing-sucker rod annulus.

46 A bottom hole pump 29 is attached to the lower end of hollow sucker rod 18. This pump may be any conventional reciprocating bottom-hole pump connected to hollow sucker rod 18. The pump 29 comprises a barrel 31 having a plunger 32 reciprocable therein and attached to rod 18. Threaded to the lower end of plunger 32 is ball valve assembly 33. A lower ball valve assembly 34 is threaded into the lower end of pump barrel 31.

47 A flexible member 36 is attached to the lower valve housing 34 by means of a skirt member 37. A hold-down shoe 38 is attached to the end of tubing 14 by means of collar 39. Springable hold-down 36 cooperates with hold-down shoe 38 to hold pump 29 in position during pumping. Pump 29 is positioned in the well so that at least its lower end is in the oil in the bottom of the bore.

48 Production from the upper zone is withdrawn from conduit 41 leading from the casing below cap 42. Gas from the lower zone is taken off through conduit 43 connected with auxiliary conduit 23 below cap 44. Oil

from the lower zone is recovered via line 46 attaching to tubing 14 below cap 47. Pumping means, not shown, is connected with sucker rod 17 above the well head.

Figures 2 and 2-A show another arrangement of pumping equipment in accordance with the invention in which corresponding parts are correspondingly numbered to those of Figure 1. In this embodiment of the invention the plunger-seal comprises a standard pump barrel 22 attached at its ends to upper and lower tubing 14. A standard pump plunger 21 having an open cage 19 and a ball check valve 20 in the upper end connects at its lower end with macaroni tubing or hollow sucker rod 18. Solid sucker rod 17 attaches to plunger 21 by means of cage 19. Check valve 20 may be omitted without adversely affecting the operation of the device.

Bottom hole pump 29 has bottom lock holddown 36 and holddown shoe 38 and grooved sealing ring 50 traversed by groove 55 which provides a passageway for gas from the lower zone into the tubing-sucker rod annulus above sealing ring 50. Stinger 48 extends from the bottom of pump 29 downwardly into the liquid from the lower production zone, which is admitted to gas anchor 49 through perforations 28. Pump 29 may, of course, be positioned at a lower level such as below packer 27 as shown in Figure 1-A.

Figure 2 shows a second embodiment of the auxiliary conduit utilized to provide gas flow from the lower zone after the gas reaches the proximity of plunger-seal 21-25. One or more openings 26 in conduit 14 are connected with a small conduit 51 by means of a ring connector or adapter 52.

Figure 3 shows another embodiment of the plunger seal in which corresponding parts are correspondingly numbered to those of the preceding figures. In this figure solid sucker rod 17 connects with a sucker rod coupling 56 which in turn connects with cage 19. Cage 19 is connected by a pull tube 57 to plunger 21, the lower end of which is attached directly to macaroni tubing or sucker rod 18. Plunger 21 is reciprocable in barrel 22. A bushing 58 closes the lower end of barrel 22 and provides a bearing for the reciprocating macaroni tubing. An adapter 59 is attached to the upper end of barrel 22 and a seating body 61 is screwed into the adapter. Seating cups 62 and seating-cup-rings 63 provide a seal between the plunger assembly and seal coupling 64 which connects directly with adjacent upper and lower tubing sections of tubing 14. A support collar 66 attached directly to seating body 61 has a flanged collar which seats against seal coupling 64. A shoe 67 and O-rings 68 between seal coupling 64 and shoe 67 provide a bottom seal for auxiliary conduit or tubing 23.

Sucker rod coupling 56 may be omitted by utilizing a cage 19 which provides a female coupling for sucker rod 17.

Operation of the pumping equipment of the invention as shown in the drawing is obvious. The solid sucker rod 17, plunger 21, hollow sucker rod 18, and reciprocating means for the same provide reciprocation of the bottom hole pump which is necessary to effect flow of oil from the lower production zone through the hollow sucker rod into the tubing-sucker rod annulus and thence to the well head. The gas which is naturally separated from the oil surrounding the pump body flows upwardly through the tubing-hollow-sucker-rod annulus to the perforations 26 in the tubing intermediate sealing means 22 and pack-off means 24 so that the gas produced in the lower zone is free to flow upwardly to the well head through auxiliary conduit 23 or 51 and to take-off line 43, without comingling with the oil flowing from lower production zone. Where desired and, as a matter of economy, parallel tubing 51 of considerably smaller size than auxiliary tubing 23 may be sealed to the flow tubing just below the perforations 26 so as to carry the gas to the well head (as shown in Figure 2).

Production from the upper zone is effected by any effective means through the casing-tubing annulus and production line 41 simultaneously or intermittently, as desired, with production from the lower zone.

Certain modifications of the invention will become apparent to those skilled in the art and the illustrative details disclosed are not to be construed as imposing unnecessary limitations on the invention.

I claim:

1. In a well bore communicating with two producing formations thru a string of casing attached to a well head, the combination comprising a flow tubing extending from the liquid at the lower producing level to the well head; a bottom hole pump within said tubing; a string of hollow sucker rod extending from the outlet of said pump to a locus above the upper producing zone; a packer intermediate said formations sealing off the annulus between said casing and said tubing; a solid sucker rod extending from adjacent the upper end of said hollow sucker rod to the well head; means connecting said solid sucker rod to said hollow sucker rod, said means having a passage for passing fluid from said hollow sucker rod to the annulus between said solid sucker rod and said tubing; sealing means between said connector means and said tubing sealing off the annulus between said tubing and said rods; a gas conduit extending from the well head to a locus intermediate said upper formation and said sealing means; conduit means for passing gas from the annulus between said tubing and said sucker rod below said sealing means into said gas conduit; and means for passing gas from said lower formation into the annulus between said hollow sucker rod and said tubing.

2. The apparatus of claim 1 wherein said gas conduit surrounds said tubing, and including a packer at the lower end of said gas conduit between said tubing and said gas conduit.

3. The apparatus of claim 1 wherein said gas conduit comprises a parallel string.

4. The combination of claim 1 wherein said means connecting said sucker rods comprises a cage.

5. The combination of claim 4 including a hollow plunger connecting said cage with said hollow sucker rod and having sealing rings in its exterior surface slidably engaging the inner wall of said tubing as said sealing means.

6. The combination of claim 1 wherein said means for passing gas from said lower formation into the hollow sucker rod-tubing annulus comprises at least one conduit thru said tubing below said packer and above said conduit.

7. The combination of claim 1 wherein said means for passing gas from said lower formation into the hollow sucker rod-tubing annulus comprises at least one conduit between said pump and the surrounding tubing bypassing said pump, said pump being above the liquid adjacent the lower formation and being provided with a stinger extending into said liquid.
